UNITED STATES PATENT OFFICE.

CHARLES D. GOLDEN, OF CHICAGO, ILLINOIS.

DESIGN FOR A CLOCK-CASE.

SPECIFICATION forming part of Design No. 26,556, dated January 26, 1897.

Application filed December 18, 1896. Serial No. 616,193. Term of patent 3 $\frac{1}{2}$ years.

To all whom it may concern:

Be it known that I, CHARLES D. GOLDEN, a citizen of the United States, residing at Chicago, in the county of Cook and State of Illinois, have invented and produced a new and original Design for Clock-Cases, of which the following is a specification, reference being had to the accompanying drawing, in which the figure is a front elevation of a clock-case, illustrating my design.

The leading feature of my design consists of a circular frame a, in the center of which is located a circular clock-face b. Upon the circular peripheral space forming the border c of the frame is a scroll c in bass relief, and between this peripheral space and that occupied by the clock-face are figures in bass relief, as follows: at the top a peacock d with its plumage displayed, at the left a child in a sitting posture grasping a pen in the right hand, and at the right another child f in a similar posture holding a book upon one knee with one hand to which he points with the other. At the bottom is represented the face of a faun g or other grotesque figure, while interspersed in said space between said respective figures is shown foliage and fruit, such as lilies-of-the-valley, roses, and grape clusters. Immediately surrounding and adjacent to the clock-face is a beaded border h.

I claim—

The design for a clock-case, substantially as shown and described.

In testimony whereof I have signed this specification, in the presence of two subscribing witnesses, this 7th day of December, 1896.

CHAS. D. GOLDEN.
